UNITED STATES PATENT OFFICE

2,462,464

IRONING CORD RETRACTOR

Ernest J. Brier, Los Angeles, and Walter G. McCue, Downey, Calif.

Application March 23, 1946, Serial No. 656,657

1 Claim. (Cl. 248—51)

1

This invention relates to an ironing cord retractor.

An object of the invention is to provide a device attachable to any conventional form of ironing board consisting of a readily bendable, but normally upright support having at its upper end a clamping or engaging means for clamping upon and supporting the cord of the iron whereby during movements of the iron in the course of ironing on the board the upright support may readily bend to accommodate such movements but will normally return to its upright position and thus hold the cord well above the clothes that are being ironed. In this manner, the cord is conveniently held and maintained against twisting and is not permitted to slide upon or be dragged across the ironed surface. As the cord is held well above the ironing board it does not interfere with movements of the iron in the course of ironing.

Another object of the invention is to provide an ironing cord retractor attachable to any conventional collapsible type of ironing board adapted to be swung into a collapsed position such as in an ironing board closet or cabinet and which has a readily bendable support which is normally in an upright position but which may be swung downwardly adjacent the board so as not to interfere with its being collapsed or put away in its cabinet.

Still a further object of the invention is to provide an ironing cord retractor consisting of a base attachable to an ironing board and which has an upstanding flange the edges of which are notched and to provide a base for a readily bendable support that is adjustably mounted on the flange and is adapted to be locked against movement relatively thereto to hold the support optionally in an upright position or in a position wherein it is pressed resiliently against the surface of the ironing board so that it cannot be readily displaced or rattle in the course of returning the board to its cabinet.

With the foregoing and other objects in view, which will be made manifest in the following detailed description and specifically pointed out in the appended claim, reference is had to the accompanying drawings for an illustrative embodiment of the invention, wherein:

Figure 1 is a perspective view of a portion of an ironing board illustrating the ironing cord retractor embodying the present invention as having been applied thereto;

Fig. 2 is a view taken substantially in the direc-

2

tion of the arrow 2 upon Fig. 1, illustrating the ironing cord retractor in side elevation;

Fig. 3 is a partial view in vertical section taken substantially upon the line 3—3 upon Fig. 2; and

Fig. 4 is a view similar to Fig. 2, but illustrating the ironing cord retractor in its collapsed position.

Referring to the accompanying drawings 10 wherein similar reference characters designate similar parts throughout, 10 indicates a conventional ironing board of the type that is pivotally mounted adjacent its rear edge 11 for swinging movement into an ironing board closet or cabinet, not shown. 12 indicates a conventional iron such as an electric iron that may be supplied with electric current through a cord 13. If the iron 12 is a gas iron, 13 indicates a flexible tube which supplies the gas to the iron.

20 The ironing cord retractor embodying the present invention comprises a suitable base generally indicated at 14 which consists of an upper body portion or plate 15 applicable to the top surface of the ironing board adjacent the remote corner 25 of the rear edge 11. Integral with this plate or body portion is a downwardly extending flange 16. These portions are apertured to receive fasteners such as attaching screws 17. The base 14 has an upstanding flange 18 in the top edge of which there is disposed a notch 19 and in the side edge of which there is disposed a second notch 20. A readily bendable support 21 is provided consisting of a lower portion 22 formed of a readily bendable spring the convolutions of which are preferably, but not necessarily, contiguous. The lower end of this spring is anchored in any suitable manner such as indicated at 23 to the horizontal portion 24 of an angular base 25 for the support. The angular base has an upright portion or flange 26 disposed adjacent the flange 18. A rivet or the equivalent indicated at 27 is rigidly fastened to the flange 18 and extends through an elongated slot 28 in the flange 26.

45 The upper portion of the support 21 may be provided by a single strand of wire indicated at 29 the top of which is given several turns to provide two closely adjacent convolutions 30 and 31 between which the cord 13 may be positioned. These convolutions serve to releasably clamp the cord at the top of the support.

In the normal position of the ironing cord retractor the horizontal portion 24 of the base 25 of the support fits within the upper notch 19 of the flange 18 and thus holds the supports 21 in an upright position. The spring 22 however, per-

mits the support to be readily bent from the upright position as indicated by dotted lines on Fig. 1. Consequently in manipulating the iron 12 the cord 13 on being pulled merely causes the support to be bent into one of the dotted line positions shown in Fig. 1. On reversely moving the iron the resiliency of the spring 22 tends to return the support to its upright position thus taking up automatically any slack in the cord 13 between the support and the iron. Consequently, the cord does not interfere with reverse movements of the iron and is held well above the clothes being ironed. Consequently dangers of twisting or crinkling of the cord 13 are thus eliminated.

When the ironing is completed the cord 13 may be detached from between the convolutions 30 and 31 and the support 21 bodily lifted. This causes the base 25 to slide upwardly relatively to the flange 18 such movement being accommodated by the rivet 27 passing downwardly through the slot 28. When the horizontal portion 24 has thus cleared notch 19 the base 25 may pivot relatively to flange 18 about the rivet 27 as a center and swung into a position as shown in Fig. 4. It will be noted that the notch 20 is more than 90° from notch 19 and on positioning the portion 24 in the notch 20 the longitudinal axis of the support as determined by the base 25 would extend downwardly through the ironing board 10. However, the spring 22 flexes slightly as indicated in Fig. 4, and causes the support to assume a slightly bent position when its base 25 is locked in the notch 20. This serves to hold the support firmly pressed against the top surface of the ironing board 10, and on storing the ironing board such as by swinging it upwardly into its cabinet the ironing cord retractor does not interfere with such collapsing movement and does not rattle due to the continual pressure exerted against the top surface of the ironing board as indicated in Fig. 4.

From the above-described construction it will be appreciated that an ironing cord retractor has been provided which serves to automatically take up slack in the ironing cord and to support the cord above the ironed surface. Furthermore, the ironing cord retractor may be collapsed into a position shown in Fig. 4, so that it will not inter-

fere with storing of the ironing board nor objectionably rattle during movements of the board. The flexing of the spring 22 in the position shown in Fig. 4 causes the base 25 to remain locked in place on the flange 18 until it is intentionally desired to restore the support to its upright position.

Various changes may be made in the details of construction without departing from the spirit and scope of the invention as defined by the appended claim.

We claim:

An ironing cord retractor comprising a bracket attachable to an ironing board, said bracket having an upstanding side in the top of which there is a notch, a resilient flexible support for an ironing cord, said support having an angular base the side of which has a limited slideable connection with said upstanding side on the bracket, and the top of which is receivable in said notch to releasably lock the support in upstanding position, said upstanding side having a second notch on its side edge disposed at more than 90° from the first mentioned notch and in which the top 15 of the angular base is also receivable whereby the support may also be locked in a position wherein it is flexed and pressed against the top 20 of the ironing board.
